UNITED STATES PATENT OFFICE.

WILLIAM HENRY HILL, OF CHICAGO, ILLINOIS.

DESIGN FOR A COVER FOR A HARVESTER.

SPECIFICATION forming part of Design No. 14,575, dated January 29, 1884.

Application filed October 29, 1883. Term of patent 14 years.

To all whom it may concern:

Be it known that I, WILLIAM H. HILL, a citizen of the United States, residing at Chicago, in the county of Cook and State of Illinois, have invented a new and original Design for Covers for Harvesters and Grain-Binders, of which the following is a specification, reference being had to the accompanying drawing.

10 This design has reference to covers for that class of machines known as "combined harvesters and grain-binders."

15 My design is fully illustrated in the accompanying drawing, which represents a plan view of my newly-designed cover.

19 The outline of the cover will be seen in the drawing. It comprises the sides and angles A a, B b, C c, D d, E e, F f, G g, H h, I i, and J j, the same being proportioned as shown in 20 the drawing hereto annexed. By this con-

figuration a neat and attractive cover is produced.

I am aware that covers for harvesters and grain-binders have been made, consisting of, mainly, rectangular pieces of material; but I 25 am not aware that such covers have been made of the design herein shown.

I claim—

The herein-described design for covers for harvesters and grain-binders, the outline of 30 said cover comprising the sides and angles A a, B b, C c, D d, E e, F f, G g, H h, I i, and J j, as herein shown.

In testimony that I claim the foregoing as my own I have hereto affixed my signature 35 in the presence of two witnesses.

WILLIAM HENRY HILL.

Witnesses:

FRANK McCANN,
W. L. MAGINNIS.
